(57) **CLAIM**

The ornamental design for a bottle cap, as shown and described.

DESCRIPTION

FIG. 1 is a top plan view of a bottle cap of a first embodiment of the present invention;

FIG. 2 is a front elevation view thereof;

FIG. 3 is a bottom plan view thereof;

FIG. 4 is a cross sectional view taken along lines 4—4 of FIG. 1 to better show the contours of the cap;

FIG. 5 is a cross sectional thereof showing the bottom lid opened;

FIG. 6 is a front elevation view thereof showing the bottom lid opened;

FIG. 7 is a bottom plan view thereof showing the bottom lid opened;

FIG. 8 is a front elevation view of a bottle cap of a second embodiment of the present invention;

FIG. 9 is a bottom plan view thereof;

FIG. 10 is a cross sectional view taken along lines 10—10 of FIG. 9 to better show the contours of the cap;

FIG. 11 is a front elevation view thereof showing the bottom lid opened; and,

FIG. 12 is a bottom plan view thereof showing the bottom lid opened.
